UNITED STATES PATENT OFFICE.

ELISHA A. PHINNEY, OF PAWTUCKET, RHODE ISLAND.

SEPARABLE BUTTON.

No. 918,588.

Specification of Letters Patent.

Patented April 20, 1909.

Application filed November 21, 1908. Serial No. 463,795.

To all whom it may concern:

Be it known that I, ELISHA A. PHINNEY, a citizen of the United States, residing at Pawtucket, in the county of Providence and State of Rhode Island, have invented certain new and useful Improvements in Separable Buttons, of which the following is a specification.

My invention relates to improvements in separable buttons and the purpose of my invention is to provide a button for use either as a collar button or a button for garments in which the back portion may be readily and quickly separated from the front portion thereof, but which will remain firmly united until the separation of the front and back portion is desired. I accomplish the purpose aforesaid by the device shown in the accompanying drawing, in which Figures 1 and 2 are vertical sections through the center of the button; Fig. 3 the releasing member; Fig. 4 a spiral spring serving to keep the releasing member normally disengaged; Fig. 5 the locking attachment; and Fig. 6 an elevation of the button, all of said views being on a somewhat enlarged scale.

The same parts are indicated by the same letters throughout the several views.

In Fig. 1, a represents the tubular post or shank of the button expanded at the lower part into a portion of the rear shield or button back a' , a^2 being the back of the shield secured to a' by being rolled over the edge thereof as at a^3 or by any other equivalent process. The upper portion of the post a is provided with an inwardly projecting flange shown at a^5 , in this case done by rolling the stem inwardly upon itself, but any other mechanically equivalent method of constructing the flange would answer equally well. The back or shield a^2 of the button is recessed and made substantially cup-shaped at the central portion as shown at a^4 for the purpose of accommodating the releasing member $b-b'-b^2$, and the spiral spring d . The releasing member $b-b'-b^2$ consists of a shank or post of circular cross section, and terminates at the upper portion in the cylindrical tube b^2 . This releasing member slides easily within the post a and is provided at its lower end with a suitable head b' . This releasing member is provided with a shoulder b^3 seen in Fig. 3 and is retained in position within the post a by this shoulder

resting upon the recessed back of the button a^4 , the portion b of the releasing member sliding easily in a circular hole in the center of the recess in the back a^2 . Between the head b' and the bottom of the recess in the back shield of the button is the spiral spring d which serves to keep the releasing member normally disengaged from the locking member hereinafter described.

The front part or head of the button is composed of the parts c^4-c^3 , these parts forming the front shield of the button and being joined by any suitable method, or the entire front shield may be made of a single solid piece. Fixed rigidly to the back surface of the front shield is the catch or locking member $c-c'-c^2$. This locking member consists essentially of a V shaped spring with one free end, rather narrow in proportion to its length, the extremity c^2 of the free limb consisting of a projecting lip adapted to engage the angular recess formed by the inward flange at the upper end of the post a . This locking member is composed preferably of a piece of spring brass or other metal bent upon itself so as to form the two limbs $c-c'$; these limbs being so arranged with reference to each other that the upper opening of the V is wider than the diameter of the opening of a at the flanged upper portion thereof so that when the front shield c^4-c^3 with the locking member fixed thereon is thrust into the flanged upper end of the post a , the limbs $c-c'$ close upon themselves sufficiently to allow the front member of the button to bring up against the flanged upper end of the post a , and the free limb of the spring $c-c'$ is then released so that the projecting lip c^2 engages the recess formed by the wall of the post a and the flanged upper extremity thereof, thus holding the front portion of the button securely in place.

When it is desired to separate the front portion from the back the head of the releasing member b' is pressed slightly inward; the upper portion of the releasing member b^2 thus engages the upper end of the free limb c^2 of the V shaped spring and releases the lip c^2 from the flanged upper portion of the post a , thus permitting the front shield c^3-c^4 to be readily separated from the remainder of the button. The lip of the free limb c' of the V shaped spring ends in an acute angle as will be seen by

reference to Figs. 1 and 2, thus insuring the locking of the front and back portion of the button together securely.

Having now described my invention what I claim and desire to secure by Letters Patent is—

1. A separable button comprising a hollow shank formed at one end with a back and at the other end formed with an in-turned flange, said back having an outwardly-projecting cup-shaped portion apertured to aline with the bore of the hollow shank, a button head engaging the other end of said shank, a catch in the form of a substantially V-shaped spring having one leg thereof secured to the inner face of the button head, said spring extending into the hollow shank with the free leg thereof engaging the in-turned flange of said shank, a releasing device comprising a post having a head on one end and the other end hollow, said head lying within the cup-shaped portion and the hollow end of said post extending into said hollow shank and receiving the free end of said catch, and a spring arranged on the post of said releasing device for normally holding the latter in a retracted position.

2. A separable button comprising a hollow shank having an inturned flange on one end thereof, a button back on the other end of said hollow shank and having an inwardly-extending cup-shaped portion open at both ends, a button head, means secured to the button head extending into said hollow shank and co-operating with said in-turned flange to secure the button head to the shank, a releasing device comprising a post having a head on one end, the other end of said post being hollow to receive the button head securing means, said post having an annular rib seating against said cup-shaped portion and limiting the movement of the releasing member in one direction, and a spring arranged on the post within said cup-shaped portion for normally holding the releasing member in a retracted position with the annular rib thereof in engagement with said cup-shaped portion.

In testimony whereof I affix my signature in presence of two witnesses.

ELISHA A. PHINNEY.
